GUARD ATTACHMENT FOR BOTTLE-CAPPING MACHINES.

1,265,058.

Specification of Letters Patent.

Patented May 7, 1918.

Application filed August 31, 1917. Serial No. 189,149.

To all whom it may concern:

Be it known that I, FRED COOPER, a citizen of the United States, residing at Bloomfield, in the county of Stoddard and State 5 of Missouri, have invented a new and useful Guard Attachment for Bottle-Capping Machines, of which the following is a specification.

The invention relates to a guard, and 10 more particularly to the class of guard attachments for bottle capping machines.

The primary object of the invention is the provision of an attachment of this character wherein the guard is movable vertically 15 and laterally in the operation of the capping plunger for the crowning of a bottle so that when the closure cap is applied to said bottle the guard will be in a position to form a barrier or gate to avoid the passage of particles of glass should the bottle be broken in 20 the capping operation of the machine, thereby protecting the operator from flying particles of glass.

Another object of the invention is the provision of a guard attachment of this character wherein on the lowering of the crowning head of the bottle capping machine the guard is automatically shifted to shielding position to avoid injury to the operator from flying 25 particles of glass should the bottle burst; and when the crowning plunger is elevated the guard is automatically shifted to one side of the capping machine to enable the operator thereof to have full access thereto for the placing or setting of a bottle to be 30 capped in the machine and arranging the cap for application to the bottle.

A further object of the invention is the provision of an attachment of this character 40 wherein the parts for operating the same and the support are readily adjustable when the occasion requires in the capping of various sizes of bottles in the capping machine.

A still further object of the invention is 45 the provision of an attachment of this character, wherein the construction thereof is novel in form to enable the attachment to be applied to the bottle capping machine without necessitating any changes in the 50 construction of the latter.

A still further object of the invention is 55 the provision of an attachment of this character which is extremely simple in construc-

tion, possesses but few parts, is thoroughly reliable and efficient in operation, automatic 55 in action, and also is inexpensive in manufacture and installation.

There are various other objects and advantages of this invention besides the above and all of which will be hereinafter more 60 fully or particularly brought out in the following specific description of the present preferred embodiment of the invention, the same being illustrated in the accompanying drawings, wherein:—

Figure 1 is a fragmentary front elevation of a bottle capping machine with the guard attachment constructed in accordance with the invention applied, the guard being shown by dotted lines in position to serve as 70 the barrier or gate, and by partly full and dotted lines at one side of the machine.

Fig. 2 is a horizontal sectional view taken through the machine above the attachment, the guard being in the position to serve as 75 the barrier or gate.

Fig. 3 is a perspective view of the guard attachment removed from the machine.

Fig. 4 is a fragmentary front elevation of the machine showing a slight modification 80 of the guard attachment.

Similar reference characters indicate corresponding parts throughout the several views in the drawings.

Referring specifically to the drawings, 85 particularly to Figs. 1 to 3 inclusive, A designates generally a bottle capping machine of that type employed for applying "crowns" and similar closure caps to bottles containing aerated beverages or other substances, and embodying in its construction a frame or casing 10, a bottle receiving socket or holder 11, a pair of vertically movable rods 12, a capping plunger 13 carried by and movable with the rods, a portion only 90 of which plunger is shown, and a treadle (not shown) forming part of the mechanism for actuating the rods. Rising from the frame or casing 10, at the top thereof on opposite sides of the bottle receiving socket 14 or holder 11 are vertical guide columns 14 for the rods 12, as shown, and carried by one of these columns is the guard attachment hereinafter fully described.

The guard attachment comprises a support 105 which is in the form of a bracket in-

cluding a substantially L-shaped bar 15, having integral therewith a depending hanger 16 which is formed with a straight vertical leg portion, a horizontal portion and 5 a substantially U-shaped bearing 17 which is offset to the horizontal portion, the latter being at right angles to the straight portion of the hanger. Mounted in the bar 15 is a clip 18 which embraces the vertical column 10 14 at the right hand side of the capping machine A, the limbs of the clip 18 being passed through the bar 15 and having threaded thereon adjustable nuts 19, for the secure fastening of the bracket upon said 15 column in the position shown in Fig. 1 of the drawings.

Swingingly supported on the bar 15 is a duplex bell crank lever 20 formed with a pivot ear 21 through which is passed a pivot 20 pin 22, which is also passed through the bar 15 and the lever 20, and in this manner the lever is swingingly mounted. Loosely connected to the arm 23 of the lever 20 is one 25 end of a link 24 which is loosely connected to the rocking standard 25 of the guard hereinafter fully described.

The guard comprises a substantially rectangular shaped plate 26, preferably made from metal riveted or otherwise secured to 30 the standard or arm 25, which lies diagonally across the plate at the outer face thereof, the standard or arm being formed with a pintle sleeve 27, through which is passed a pintle or pivot 28 fixed in the bearing 17 35 for swingingly connecting said standard or arm thereto. The plate 26 is formed with an inwardly extending flange 29 co-extensive with one long and one short edge thereof to serve as a deflector to avoid the scattering or flying of small particles of glass when the plate is thrown to position to act 40 as a barrier or gate to the capping machine.

On the upper end of the rod 12 is detachably secured a bracket 30, through an opening 45 of which is passed an actuating rod 31, which is formed with a crank end 32 pivotally engaged in the arm 33 of the bell crank lever 20, the rod 31 being threaded at its upper end which is passed through the 50 bracket 30 and carries the adjustable nuts 34, so that in this manner the throw of the rod can be varied for the successful operation of the guard attachment synchronously with the bottle capping machine.

55 Connected in any suitable manner to the base 35 of the frame or casing 10 is one end of a coiled retractile spring 36, which has its other end detachably engaged with a short link 37 which is loosely connected to 60 the arm 33 of the bell crank lever 20, and this spring 36 tensions the bell crank lever for the automatic action of the guard attachment in the operation of the capping machine.

65 It will be apparent that when the plunger

13 is in elevated position, and the bell crank lever 20 has been thrown under the action of the operating rod 31 against the resistance of the tension of the spring 36 to one side of the capping machine A, free access can be 70 had to the parts of the machine for the purpose of setting the bottle to be capped into position and arranging the cap for application thereto. On the lowering of the plunger 75 13, the spring 36 becomes active upon the bell crank lever 20 to move the same to the position shown in Fig. 2 of the drawings, whereupon the guard has been shifted to operative position as a barrier or gate for protection between the bottle and the operator 80 standing at one side of the machine to arrest all flying particles of glass if the bottle should burst while being capped, and prevent such particles from coming in contact with and injuring the person or clothing of the operator.

In capping bottles containing highly charged aerated beverages, it frequently happens that the bottle bursts under pressure in the capping operation, with resultant 90 liability of injury to the operator from the particles of flying glass. By constructing the guard attachment in the manner described when the same is in operative position as a barrier or gate, it serves to stop 95 all large particles of glass and also prevents any small particles of glass from flying in the direction of the operator of the machine.

In Fig. 4 of the drawings, in lieu of mounting the specific form of bracket 30 shown in Fig. 1 upon the upper end of the rod, there is substituted the form of bracket 37 which is clamped upon the rod 12 at any desired point, so that the length of the rod 38 which corresponds to the rod 31 in Fig. 1 100 of the drawings can be materially shortened, and in this arrangement the guard attachment will automatically operate with the capping machine which is set for short 105 length bottles, the other parts of the attachment being constructed identically in the manner as hereinbefore set forth.

In the operation of a crown bottle capping machine, the operator must have free access 115 to both sides of the machine during the changing of bottles, and the placing of caps in the crowning head. The crowning head after receiving the cap is then lowered, until the rubber throat gasket comes in contact with the neck of the bottle, thus making the 120 connection between the crowning head and the bottle airtight and capable of holding pressure. As the liquid fills the bottle, the air must be released, this may be done by properly manipulating the left hand. Usually most operators, however, find it faster work to use the foot for operating the foot treadle (known as sniffing by foot) to cause 125 the crowning head to rise up off of the bottle, allowing the air to pass out, and thereby 130

be released from the bottle. After the bottle has been filled to the desired level, the crowning head is lowered to crimp the cap on the mouth of the bottle, whereupon the 5 crowning head is then moved to its initial raised position by the mechanism within the casing of the machine. As the head approaches the initial position, the cap for the next operation of the machine, is usually 10 placed in said head. Therefore, a guard to be safe and successful in its work, must not interfere with any of these operations.

When the crowning head is at its uppermost position, the guard is held out of the 15 way, so that there is no inconvenience in the handling of the bottles. As the crowning head is lowered, the spring 36, connected to the base 35 of the machine A, and to the lever 20, throws the guard 26 over to one 20 side of the bottle holder, through the medium of the lever 20, and the link 24 connecting it to the standard 25, carrying the guard plate 24, the guard being arrested when reaching operative position by the 25 lever 20, contacting with the bar 15 of the bracket.

The guard attachment has no effect on the machine's operation during the filling and crowning of the bottles.

30 It will be observed that the guard attachment is operated by the spring 36, which throws the guard into safety position, when permitted to do so by the downward stroke of the crowning head or plunger 13, and this 35 spring is connected with the lever 20, which multiplies the motion of the parts, thus moving the guard through an arc approximately 90 degrees, with not over one inch travel of the crowning head or plunger. The guard 40 is practically independent from the moving parts of the crowning machine after reaching safety position, because the motion of said guard is stayed by the striking of the lever 20, against the bar 15 of the bracket.

45 The bracket 30 is not fixedly connected to the rod 31, but slides along the same after the guard reaches safety position, and until such position is reached, the nut 34 rests on the bracket 30. Likewise the bracket 37^a is 50 not permanently fixed to the rod 38, but operates to slide along the rod after the guard reaches safety position, and until this position is reached, the nut on said rod 38 rests against the bracket 37^a.

55 From the foregoing description it will be seen that the invention provided a guard or protector which may be applied to any ordinary type of capping machine, and also at either side of such a machine to protect and 60 prevent injury to the operator, if from any cause, a bottle should burst during the capping operation.

It is to be understood that changes, variations and modifications may be resorted to, 65 such as come properly within the scope of

the appended claims without departing from the spirit of the invention or sacrificing any of its advantages.

What is claimed is:

1. In a guard for bottle capping machines, 70 the combination, with the main frame of the machine, the reciprocating capping plunger and the plunger carrying rods, of a bracket detachably fixed to the frame, an arm pivoted for vertically swinging movement in 75 said bracket, a guard carried by said arm and movable thereby in front of the bottle holder to constitute a barrier or to inoperative position at one side of the machine, and means connected with one of the plunger 80 carrying rods for automatically operating the arm to bring the guard to barrier position or to inoperative position on the lowering and ascending of the plunger.

2. In a guard for bottle capping machines, 85 the combination with the frame, the reciprocating capping plunger and the plunger rods, of a bracket detachably fixed to the machine, an arm pivoted in said bracket for vertical swinging movement, a guard carried 90 by said arm and movable thereby in front of the bottle holder to constitute a barrier or to inoperative position at one side of the machine, means connected with one of the plunger carrying rods for automatically operating the arm to bring the guard to barrier 95 position or to inoperative position on the lowering and ascending of the plunger, said means including tension means for the automatic operation of the guard synchronously with the operation of the machine.

3. In a guard for bottle capping machines, the combination with the main frame of the machine, the reciprocating capping plunger and the plunger carrying rods, of a support 105 upon the frame, a vertically swinging guard plate movable to operative and inoperative positions, a swinging arm for the guard plate pivoted in the support, a bell crank lever pivoted on the support, a connection between one arm of the lever and the arm for the guard plate, and a connection between one of the plunger carrying rods and the other arm of the lever.

4. In a guard for bottle capping machines, 115 the combination with the main frame of the machine, the reciprocating capping plunger and the plunger carrying rods, of a support upon the frame, a vertically swinging guard plate movable to operative and inoperative 120 positions, a swinging arm for the guard plate pivoted in the support, a bell crank lever pivoted on the support, a connection between one arm of the lever and the arm for the guard plate, and a coiled retractile 125 spring connected with the base of the machine frame and with said lever.

5. In a guard for bottle capping machines, the combination with the main frame of the machine, the reciprocating capping plunger 130

and the plunger carrying rods, of a support upon the frame, a vertically swinging guard plate movable to operative and inoperative positions, a swinging arm for the guard plate pivoted in the support, a bell crank lever pivoted on the support, a connection between one arm of the lever and the arm for the guard plate, and an adjustable connection between one of the plunger carrying rods and the other arm of the lever.

6. In a guard for bottle capping machines, the combination with a machine having a reciprocating capping plunger, of a vertically swinging guard mounted upon the frame of

the machine, said guard embodying a plate, a pivoted swinging arm carrying said plate, a bracket supporting the arm, a lever pivoted to the bracket, a bracket fixed to the plunger, a rod engaged in the last named bracket and connected to the lever, a link connecting the lever to the arm at one side of the axis of movement of said lever, and resilient means connected to the lever at the other side of the axis of movement thereof.

7. In a guard for bottle capping machines, the combination with a machine having a reciprocating capping plunger, of a vertically swinging guard mounted upon the frame of the machine, said guard embody-

ing a plate, a pivoted swinging arm carrying said plate, a bracket supporting the arm, a lever pivoted to the bracket, a bracket fixed to the plunger, a rod engaged in the last named bracket and connected to the lever, a link connecting the lever to the arm at one side of the axis of movement of said lever, and a coiled retractile spring connected to the lever at the other side of its axis of movement and also connected to the frame of the machine.

8. In a guard for bottle capping machines, the combination with a machine having a reciprocating capping plunger, of a vertically swinging guard mounted upon the frame of the machine, said guard embodying a plate, a pivoted swinging arm carrying said plate, a bracket supporting the arm, a lever pivoted to the bracket, a bracket fixed to the plunger, a rod engaged in the last named bracket and connected to the lever, a link connecting the lever to the arm at one side of the axis of movement of said lever, a coiled retractile spring connected to the lever at the other side of its axis of movement and also connected to the frame of the machine, and a clip detachably connecting the first named bracket to the frame of the machine.

9. The combination with a reciprocating plunger of a bottle capping machine, of a guard pivotally mounted on the machine for movement edgewise, a bell crank lever connected to the guard, a spring connected to the bell crank lever for moving the guard to operative position in front of the bottle

holder in the machine, upon the downward movement of the plunger, and a loose connection between the plunger and bell crank lever for moving the guard to inoperative position at one side of and beyond the machine upon the ascent of said plunger.

10. The combination with a reciprocating plunger of a bottle capping machine, of a guard pivotally mounted on the machine for movement edgewise, a spring for moving the guard to operative position in front of the bottle holder in the machine upon the downward movement of the plunger, and a motion multiplying lever connection between the plunger, the spring and the guard for moving the latter to inoperative position at one side of and beyond the machine upon the ascent of said plunger, said guard moving in an arc approximately 90 degrees with a limited travel of the plunger, and means contacting with the frame of the machine to arrest the movement of the guard to operative position.

11. The combination with a plunger of a bottle capping machine, of a guard pivotally mounted on the machine at one side of the bottle holder of said machine for movement edgewise, a motion multiplying lever connected to said guard, a spring connected to said lever for moving the guard in the arc of a circle from a position beyond the machine to a position in front of the bottle holder, and a connection between said lever and said plunger to return said guard to its inoperative position, said connection being loose so that upon the downward movement of the plunger the spring is free to move the guard through the motion multiplying lever.

12. The combination with the plunger of a bottle capping machine, of a guard pivotally mounted on the machine at one side of the bottle holder of said machine for movement edgewise, a motion multiplying lever connected to said guard, a spring connected to said lever for moving the guard in the arc of a circle from a position beyond the machine to a position in front of the bottle holder, a bracket connected to the plunger, a rod connected to the motion multiplying lever and passed through the bracket, and a nut adjustable on the rod, whereby upon the downward movement of the plunger the bracket slides on the rod and the spring through the motion multiplying lever moves the guard to operative position, and upon the upward movement of the plunger, the guard is returned to its inoperative position.

13. The combination with the plunger of a bottle capping machine, of a guard pivotally mounted on the machine at one side of the bottle holder of said machine for movement edgewise, a motion multiplying lever connected to said guard, a spring connected to said lever for moving the guard in the arc of a circle from a position beyond the

machine to a position in front of the bottle holder, and a rod connected to the motion multiplying lever and having a loose connection with the plunger, which permits the 5 plunger to work downwardly without affecting said connection so as to allow the spring to move the guard through the motion multiplying lever to its operative position.

In testimony that I claim the foregoing as my own I have hereto affixed my signature in the presence of two witnesses.

FRED COOPER.
